Primary Examiner — George D. Kirschbaum*Assistant Examiner* — Maria J Edwards(74) *Attorney, Agent, or Firm* — Husch Blackwell LLP(57) **CLAIM**

The ornamental design for a “baseball glove,” as shown and described.

DESCRIPTION

FIG. 1 is a top perspective view of a baseball glove, showing our new design;

FIG. 2 is a front perspective view thereof;

FIG. 3 is a back perspective view thereof;

FIG. 4 is a left side perspective view thereof; and,

FIG. 5 is a right side perspective view thereof.

The broken lines represent portions of the baseball glove and form no part of the claimed design.

1 Claim, 5 Drawing Sheets(56)
